**TWIN WIRE PAPER-MAKING METHOD IN WHICH
CONTROLLED DEWATERING IN TAPERING GAP
CAUSES SUSPENSION TO MOVE AT SPEED OF
WIRES**

BACKGROUND OF THE INVENTION

The invention relates to a paper making method employing a machine with two wires joining into a double wire area and confining in front of said area a narrow converging gap for sheet forming.

Such machines are known. As other known paper making machines, such machines have the disadvantage that the formed sheet is composed of layers with fibres orientated in the plane of said layers. With increasing wire speed and decreasing consistency of the suspension the layers get more distinct. The single layers are badly connected to each other. Besides, most of the fibres in the layers are orientated in the direction of wire travel, resulting in different strengths of the sheet in longitudinal and lateral direction.

Paper making method in which turbulent suspension under pressure is introduced to a tapering gap between a pair of traveling wires at the speed of the wires, and is dewatered therein by suction applied in a series of zones along the wires in such controlled manner that the quantity of liquid in the suspension decreases from zone-to-zone proportionally to gap width, and the suspension is caused to move through the gap at essentially the speed of the wires and without being subjected to substantial mechanical pressing by the wires.

SUMMARY OF THE INVENTION

The purpose of the invention is to provide a paper making method in which the machine delivers in a wet process a sheet having a fibre orientation distributed on all dimensional directions equally, and which can utilize high wire speeds.

According to the invention, at least 30%, and preferably more than 50%, of web formation takes place in the converging gap, and the suspension is fed to the gap in a turbulent condition and under a pressure which causes it to enter at the speed of the wires. The suspension is dewatered by suction applied in a series of zones positioned along the path of travel of each wire, and the degree of suction dewatering in each zone is set so that the quantity of liquid in the suspension decreases from zone-to-zone in the direction of wire travel proportionally to the width of the gap. This technique causes the suspension to move through the gap at essentially the speed of the wires and without being subjected to appreciable mechanical pressing by the wires.

The fibres coming in a turbulent suspension into the gap maintain their orientation in all dimensional directions even during depositing on the wires. Good sheet quality is especially achieved if the quantities of liquid to be sucked away in the zones, and/or the width of the gap is so adjusted that the suspension has reached the frozen condition at the outlet of the gap. Under frozen condition is understood the condition wherein the fibres cannot change their orientation because of the short distance from each other, and the co-travelling of the wires. This condition is reached at least at consistencies of 3 to 6% with short fibre lengths (1 to 6 mm), and at consistencies of 0.5 to 1% with long fibre lengths (6 to 30 mm).

The gap defined by the wires has a length of 300 to 2,000 mm, an inlet width of 6 to 100 mm, and an outlet width of up to 5 mm. Each dewatering zone preferably has a length, measured in the direction of wire travel, of 60 to 150 mm, and is provided with a wire supporting surface having a radius of curvature of 1,000 mm to infinite. These zones are equipped with separate devices for adjusting the quantities of liquid to be sucked away. It is of great advantage if the dewatering elements are stationary suction boxes having perforated wire supporting walls which are convex domed against the wires. Manufacturing costs are reduced if the surface of the convex domed wall has the form of a cylinder section, the generatrix of which is an arc of a circle with a sector angle of less than 15°. The domed walls guarantee, under the tension of the wires, a smooth joining of each wire to the surfaces of the boxes, resulting in a definite distance between the wires and the boxes and minimal by-passing of air. Therefore, in each zone a definite vacuum can be established, and a definite quantity of liquid can be sucked away.

For adjusting the machine in respect of the kind of suspension, the kind of sheet to be formed, or different wire speeds, advantageously the width of the inlet and/or outlet of the gap is adjustable. Equally, the radius of curvature of the dewatering elements can be adjustable. For this purpose, the dewatering elements can be made of links turnable against each other, or can be substitutable by elements with another radius of curvature. In the latter case, the length (in wire travel direction) of the element is adjustable too.

Deposition of the fibres on the wires can be advantageously influenced, while maintaining equal speeds for suspension and wires, by having the quantity of liquid to be sucked away at one side of the gap bigger than at the other side of the gap, and then the quantity of liquid at the other side of the gap bigger than at the one side of the gap, alternating in direction of wire travel. The result is a suspension flowing in the form of a serpentine through the gap.

Orientation of the fibres in the suspension can also be influenced by adjusting the quantities of liquid to be sucked away so as to have for one or some zones a certain speed difference between suspension and wires. Neglecting this, that is taken essentially, the suspension is kept at the same speed as the wires.

BRIEF DESCRIPTION OF THE DRAWINGS

Embodiments of the invention are described herein in detail with reference to the accompanying drawings in which:

FIG. 1 shows a vertical section, in the direction of wire travel, through a paper making machine

FIG. 2 a corresponding vertical section through part of another embodiment, and

FIGS. 3 and 4 show each one form of a gap and dimensioning data for further gaps.

**DESCRIPTION OF THE PREFERRED
EMBODIMENTS**

The paper making machine shown in FIG. 1 has two wires 1 and 2 which join into a double wire area 3. In front of the double wire area 3, immediately before the wires 1, 2 join into area 3 the wires 1, 2 form a converging gap 4 between themselves. The length of the gap 4 is 300 to 2,000 mm. The width of the gap 4 is at the inlet 4¹ of the gap 6 to 100 mm, and the width of the

gap is at its outlet 4² some tenth of millimeter to 5 mm. The wires 1 and 2 travel over dewatering elements 5 and 6, respectively, arranged on both sides of the gap 4. The dewatering elements are subdivided into a plurality of zones, i.e. into zones 7, 9, 11, 13, 15 and 8, 10, 12, 14, 16, respectively. Each of the zones has an adjusting device—not shown—for adjusting the quantity of the liquid to be sucked away in the respective zone. Dewatering elements 17 and 18, arranged in front of the inlet 4¹ also each have an adjusting device—not shown—for adjusting the liquid to be sucked away. The dewatering elements can be moved—by means not shown—relatively to each other so as to make the width of the gap 4 at the inlet 4¹ or at the outlet 4² bigger or smaller.

A chamber 19 for feeding suspension to the gap 4 opens against the inlet 4¹, i.e. the lower end of gap 4. This chamber 19 has two feeding conduits 20, 21 arranged symmetrically to the gap 4, and a return conduit 22, for the suspension.

The inlet width (4¹) of the gap 4 and the pressure of the suspension to be lead to the gap 4 are so adjustable as to make the speed of the suspension at the inlet 4¹ equal to the speed of the wires 1, 2. The quantities of liquid to be sucked away with the zones 7 to 16 are so adjustable as to make the speed of the suspension along the gap, i.e. from the inlet 4¹ to the outlet 4² essentially equal to the speed of the wires 1, 2. Thereby, the quantities of liquid to be sucked away with the zones and/or the width of the gap 4 are so adjustable as to have reached at least at the outlet 4² of the gap 4 a consistency at which the suspension is in the frozen condition.

The dewatering elements 17, 18 at the transition between chamber 19 and inlet 4¹ are formed as stationary suction boxes with a perforated wire-supporting convex domed wall. In the chamber 19 are inserted turbulence generators, i.e. rotatable perforated rollers 23, 24, rotatable bodies 25, 26 and a rotatable cylinder 27.

An element of the chamber 19, that is the wall of said chamber can be set under oscillations with periodic frequencies of more than 5 per second, by a vibrator 28. Similarly, vibrators 29 and 30 serve for oscillating the dewatering elements 5 and 6, respectively with periodic frequencies of more than 50 per second. The direction of oscillating is at an angle of at least 20 degrees relatively to the plane of the wires, i.e. as for the vibrator 28 an angle of 30°, and for the vibrators 29 and 30 an angle of 90°.

The suspension has in the chamber 19 practically constant consistency. In the gap 4, the consistency increases with short fibre lengths (1 to 6 mm) from 0.1 to 1.5% at the inlet 4¹ up to 3 to 6% at the outlet 4². With long fibre lengths (6 to 30 mm), the consistency increases from 0.001 to 0.1% at the inlet 4¹ up to 0.5 to 1% at the outlet 4². Thereby, with the invention, very high wire speeds can be achieved, even with the higher consistencies.

In the double wire area 3 in which the two wires 1, 2 support the formed sheet at both sides, the dewatering process can be brought up to 44% consistency, i.e. solids per solids plus liquid, with the help of boxes 31 having perforated wire-supporting convex domed walls, grooved cylinders 32, and a pair of cylinders 33.

The gap 4 is arranged vertical and converges in direction of wire travel from below to above. The suspension flows upward in the gap 4.

With the embodiment according to FIG. 2, the gap 4 is arranged vertically too, yet the gap converges downwards, and the suspension flows downwards. The chamber for feeding the suspension to the gap 4 is formed as a box 34 the bottom of which is formed by the wires 1 and 2. In the box 34, a bath of suspension is maintained. Under the box 34, suction boxes 35 and 36 are arranged. Part of sheet forming takes place on the wires 1, 2 before these wires enter the gap 4. The layer of the sheet lying between the layers formed in box 34 are then formed in gap 4 according to the invention.

The quantities of liquid to be sucked away in the zones of the gap 4 are so adjusted as to make the speed of the suspension along the gap essentially equal to the speed of the wires. Maintaining this condition, alternating from zone to zone in the direction of wire travel, firstly, at one side of the gap 4 is sucked away a bigger quantity of liquid than at the other side of the gap 4, then at said other side of the gap is sucked away a bigger quantity of liquid than at the one side of the gap, then in the, in the direction of wire travel, third zone vice versa. That is, the quantity in zone 7 is bigger than in zone 8, in zone 10 bigger than in zone 9, in zone 11 bigger than in zone 12, in zone 14 bigger than in zone 13, in zone 15 bigger than in zone 16. The stream of suspension in gap 4 gets therefore the form of a serpentine.

For acting on the fibres in the direction of flow, the quantities of liquid to be sucked away in the zones are so adjusted that with a pair of zones, i.e. with the zones 9 and 10, a difference of speeds between suspension and wires occurs. Such a local acceleration or retardation could be repeated in further pairs of zones. Especially if accelerated and retarded zone pairs alternate, the speed of the suspension can be in general kept equal to the speed of the wires all the same.

The ends of the dewatering elements 5 and 6 are staggered relatively to each other at the outlet 4² of gap 4. This is advantageous with small widths of the outlet 4². With the box 34, more than two feeding and/or return conduits open into it, that is the feeding conduits 37 and 38, and the return conduits 39 and 40. The kind of sheet forming in the box 34 as well as the condition of the suspension delivered to the gap 4 can thereby be influenced.

The walls of the dewatering elements 5 and 6 are lightly convex domed against the wires, and have the form of a cylinder section the generatrix of which is an arc of circle with a big radius. The surface of the convex domed wall is made of a material having a coefficient of friction of smaller than 0.1 relatively to a wire made of metal.

With the gaps given with FIG. 3 the sketch at the left side of the drawing shows an inlet width d_1 , an outlet width d_2 , and a length 1 of the gap. The gap is in the drawing confined by two arcs of circle, each of them reaching from the inlet to the outlet of the gap, and having a radius r and a sector angle α . The gap is subdivided into twelve zones of equal length. At the right hand of the sketch, a table gives the portion of the liquid to be sucked away, which is left in the suspension at the end of each zone (in % of the total quantity of liquid to be sucked away in the whole gap) for four dif-

ferent forms of gap. The length 1 of the gaps is equal with all forms, namely 1,200 mm, while the difference d between inlet width d_1 and outlet width d_2 as well as the radius r and the corresponding sector angle α are different.

FIG. 4 corresponds to FIG. 3. Yet, the length 1 of the gaps is 500 mm and the gaps are subdivided into five zones. There are seven different forms of gaps.

With the shown forms of gaps, the table given quantity of liquid decreases in the direction of wire travel from zone to zone proportionally to the width of the gap. The difference between the total quantity (100%) and the quantity given in the table has to be sucked away at the respective zone end. This way the speed of the suspension in the gap is constant. As to make this speed exactly constant, the perforations of the suction boxes can differ with a zone in the direction of wire travel in respect of form and/or size.

With the gap forms according to FIG. 3, the total quantity of liquid to be sucked away in the gap is 40,000, with the FIG. 4 forms 30,000, liter per minute and meter lateral width of the sheet.

In order to feed the suspension into the gap 4 with wire speed the suspension has to be fed to the chamber 19 with a pressure that is higher than the pressure corresponding to wire speed. Table 1 shows the respective pressures (meter water column) for some wire speeds (meter per minute).

The width (mm) of the inlet 4¹ of the gap 4 is a function of the quantity of suspension (liter per minute and meter lateral width of the sheet) flowing through the gap and of the wire speed. For equal speeds of suspension and wires, Table 2 shows some examples.

In Table 3, the production of paper (Kilogramm per minute and meter lateral width of the sheet, or metric tons per 24 hours and meter lateral width of the sheet) is given as a function of consistency (per cent) and quantity of suspension flowing through the gap.

The production of the machine according to the invention furthermore depends on the degree of freeness, the dewatering or suction area, the weight of square meter of paper, and the dewatering vacuum or suction pressure. Dewatering on the double wire system, that is from two sides of the sheet, and up to consistencies of 1 to 6% results in big quantities of liquid sucked away. In Table 4, the quantities (liter/per minute and square meter suction area) are given for some kinds of suspension, dependent on different suction pressures (meter water column).

Table 5 shows for a suction box with plane wire-supporting wall (radius of curvature being infinite) and a length of 1 meter, subdivided into 10 zones, the quantity of liquid to be sucked away with each zone. With 1 meter lateral width of the sheet, each zone has a suction area of 1,000 cm². The quantity of liquid (liter per minute) is given dependent on wire speed (meter per minute) and width d (mm) of the gap.

By adjusting the width d of the gap (10 bis 80 mm) and the suction pressure (2 to 8 m water column) any quantities of liquid to be sucked away with the production of the different paper quantities are easily coped by the invention.

Table 6 shows production capacities for paper made of synthetic fibres, dependent on fibre lengths and corresponding consistencies of the suspension.

Combining Tables 2 to 5 one can see that the limitations of width of the gap, wire speed, quantity of liquid to be sucked away, length of the suction boxes, and production capacity are a function of the consistency of the suspension.

Suspensions with long fibres for non-woven webs can be dewatered according to the invention with wire speeds of 1,000 to 1,200 m per minute, widths at the inlet of the gap of 40 to 70 mm, and quantities of suspension of 48,000 to 70,000 liter per minute and lateral width of the sheet.

With short fibre suspensions, wire speeds of 1,000 to 1,500 m per minute, and width at the inlet of the gap of 20 mm, the production of paper with the machine according to the invention reaches 100 to 300 kg per minute and m lateral width of the sheet.

The width d_1 at the inlet 4¹ of the gap 4 has to be bigger than the length of the fibres. As shown, this condition can be met with the invention.

Under "paper making machine" and "paper" is also understood, in the sense of this specification, a machine which produces a paper-like sheet, for example a machine for producing non-woven webs.

I claim:

1. A paper making method in which at least 30% of the forming of a continuous sheet is effected by dewatering a fiber suspension in a tapered gap defined by

20 a pair of traveling wires, the method comprising the steps of

a. establishing and maintaining, in a region adjacent the gap inlet, a volume of fiber suspension which is under pressure, has uniform consistency, and is in a turbulent state,

b. said pressure being such as to cause suspension to flow into the gap at the speed of the wires;

c. causing the wires to pass in contact with suspension in said region immediately before they define said gap;

d. withdrawing liquid from the suspension in said region through each wire by suction to thereby cause deposition of fibers on the wires and effect partial formation of the sheet;

e. withdrawing liquid from the suspension in the gap through each of the wires by suction applied in each of a series of separate zones positioned along the path of travel of the wire, whereby the consistency of the suspension increases gradually as the suspension travels through the gap and a sheet is formed therefrom between the two wires; and

f. setting the degree of suction dewatering effected in each zone so that the quantity of liquid in the suspension decreases from zone-to-zone in the direction of wire travel proportionally to the width of the gap, and the suspension is caused to move through the gap at essentially the speed of the wires and without being subjected to appreciable mechanical pressing by the wires.

2. A method as defined in claim 1 in which a. withdrawal of said liquid in the gap is effected through two sets of suction boxes having perforated wire-supporting walls which are convex domed against the wires,

b. whereby contact between the wires and the walls minimizes by-passing of air into said boxes and insures withdrawal of definite quantities of liquid in said zones.

3. A method as defined in claim 1 in which a. the quantities of liquid withdrawn through the two wires in each zone are unequal; and

b. in adjacent zones the greater quantity is withdrawn through different wires,

c. whereby the suspension in the gap has a tendency to form a serpentine.

4. A method as defined in claim 1 including the step of continuously circulating suspension through said region between a plurality of feeding and return conduits.

5. A method as defined in claim 1 including the step of vibrating suspension in said region at a frequency greater than 5 cycles per second.

6. A method as defined in claim 1 including the step of vibrating suspension in the gap at a frequency greater than 50 cycles per second.

7. A method as defined in claim 6 in which the suspension in the gap is vibrated in a plane forming an angle of at least 20° with the planes of the wires.

8. A method as defined in claim 1 in which turbulence in said region is produced mechanically by a rotating body.
